TELEPHONE SYSTEM

Francis Tatlock Belas, Liverpool, England, assignee to Associated Telephone and Telegraph Company, Chicago, Ill., a corporation of Delaware

Application March 25, 1931, Serial No. 525,182
In Great Britain March 27, 1930

30 Claims. (Cl. 179—27)

The present invention relates to telephone systems and has for its object the provision of a new and improved train of automatic switches for use in such systems.

5 The invention is concerned with the provision of arrangements for enabling a toll operator to establish connection with a line which is already engaged in a local connection. This is effected by providing combined local and toll final selector with two sets of line wipers and arranging the connections in the subscriber's line circuit so that the subscriber's line is always taken into use over a particular set of wipers so that when a toll operator desires to disconnect the wanted 10 subscriber from a local connection, the subscriber's line is disconnected from the local switches but remains accessible to the other set of wipers of the final selector switch.

According therefore to one feature of the invention in a telephone system a wanted line is accessible over two paths one of which is accessible only to privileged parties the other path being disconnected when the path accessible only to privileged parties is taken into use.

25 According to a further feature of the invention in a telephone system having local and toll calls extended to a wanted line over automatic switches a relay individual to the wanted line is adapted to be controlled from the toll board to effect the disconnection of the wanted line from automatic switches over which the wanted line is engaged in a local call.

According to a further feature of the invention in a telephone system having subscribers' lines accessible over one route to non-privileged parties and over a different route to privileged parties a connection established over the second route automatically prevents subsequent connections being extended to a line over either route.

40 According to a still further feature of the invention in a telephone system a connector switch adapted to be used in both toll and local connections is provided with two sets of wipers one set of which is accessible to calling subscribers whilst the other set is accessible only to operators.

These and other features of the invention will be better understood from the following description of a preferred embodiment of the invention, taken in conjunction with the accompanying drawings comprising Figs. 1 to 14 which should be arranged as shown in the key sheet Fig. 15 to form a complete circuit.

Fig. 1 shows the subscriber's line cut-off and toll breakdown relay circuit arranged for toll breakdown and also suitable for use when it is

required to provide the arrangement for disconnecting the finder switch if the calling subscriber does not dial within a predetermined period.

Fig. 1a shows the subscriber's line circuit without this latter facility but arranged for toll breakdown and is intended to replace Fig. 1 when "toll breakdown" only is required. 60

Fig. 2 shows a typical finder switch.

Fig. 3 shows a typical local first selector possessing a digit absorbing feature. 65

Fig. 4 shows a combined regular and toll final selector.

Fig. 5 is meant to illustrate the called subscriber's line cut-off and toll breakdown relays and is substantially the same as Fig. 1. 70

Figs. 6 and 7 are similar and show the finder distributor circuit for A and B groups respectively, and also includes the emergency change-over arrangement in case either distributor switch should become faulty.

Fig. 8 shows a typical incoming or toll selector not including the digit absorbing feature.

Fig. 9 shows an auto-to-auto repeater utilized in the repeating of impulses to the selectors at a distant exchange. 80

Fig. 10 shows the main and extended alarm relay group.

Fig. 11 shows a relevant portion of a toll operator's cord circuit.

The left-hand half of Fig. 12 shows the delayed alarm circuit arranged for a 36 seconds delay and used in connection with the finder switches, the right-hand half of Fig. 12 shows the release alarm supervisory equipment. 85

Fig. 13 shows a delayed alarm equipment arranged for a three minute delay used in connection with the final selectors and. 90

Fig. 14 shows the equipment utilized in the generation and distribution of ringing and tones. 95

Referring now to the assembled circuit, when a subscriber desires to originate a call he will lift his receiver from the switch hook in the usual manner thereby completing a circuit across the conductors 10 and 11, Fig. 1, for operating relay LR over its upper winding. Relay LR in operating at armature *lr1* removes earth from the conductor 13 to mark the appropriate position in the finder bank multiple, at armature *lr2* extends earth by way of the resting armature *col* over conductor 14 which represents the finder start common to operate the start relay A in the "A" group finder distributor circuit, Fig. 7. The operation of the finder distributor is described in detail in British Patent No. 333,182 from which it will be seen that it includes ar- 105

rangements for setting a second finder in operation if the first finder is not connected to the calling line within a predetermined period. One difference that should be mentioned however is 5 that the finders in the present application are 100 point finders and are not arranged to give preferential service. Each finder is permanently linked with a first selector which is of the two 10 directional type familiar to those skilled in the art, with the addition of an extra relay F and normal post springs NP for causing the selector to drop back from certain levels. In addition there is a common delay set, Fig. 12, provided for each group of finders for the purpose of giving 15 an alarm and disconnecting the calling line if the calling subscriber fails to dial within a predetermined period. This is accomplished in the following manner.

When the finder which has been allocated by 20 the distributor has found the calling line in the manner described in the previously mentioned patent and switched through to its associated local first selector, Fig. 3, relay 2A of the latter switch operates over the circuit including the calling subscriber's instrument and at armature 2a1 extends earth from resting armature 1h3 to operate relay 2B.

In addition to performing functions which will be described later relay 2B at armature 2b1 completes the circuit from earth to conductor 23 and thence via resting armature zp_1 , operated armature h_1 , resting armature zp_2 , wiper 3a and bank contact associated with the calling subscriber, conductor 13, operated armature l_1 , lower winding of relay LR and winding of relay CO in series to battery. Relay LR holds over this circuit and relay CO operates, at armature co_1 removing earth from the finder start common conductor 14 and at armatures co_2 and co_3 clearing the talking conductors 24 and 25 of attachments. Armatures co_2 and co_3 also have other functions to be described later. Relay 2B, Fig. 3, also at armature 2b2 earths conductor 15 to operate the motor start relay MS, Fig. 8, at armature 2b3 prepares the impulsing circuit for the vertical magnet 2VM and at armature 2b4 connects up conductors 26 and 27 in order to complete the circuit of relay SP, Fig. 2, which operates from battery, upper winding of relay SP, conductor 26, operated armature 2b4, conductor 27, resting armature zp_3 , conductor 28, home contact of bank 2 of delayed alarm rotary switch DAR, Fig. 12, wiper 2b to earth. Relay SP at armature sp_1 locks up in a circuit extending from battery upper winding of relay ZP, operated armature sp_1 , lower winding of relay SP, conductor 29, over operated armature 2b6 to earth. Armature sp_2 prepares a circuit for the lower winding of relay ZP. Relay MS, Fig. 8, in operating at armature ms_1 provides earth over conductor 30 for effecting the operation of relay ST, Fig. 12, and at armature ms_2 maintains earth on the motor start conductor 16 which was originally applied at armature a_1 , Fig. 7, to set in operation the ringing and tone equipment, which in addition to other functions applies earth pulses at intervals of 9 seconds to the "S" pulse conductor 17 by the agency of the spring set and associated cam S, Fig. 14. Relay ST on operating 70 at armature st_1 opens the homing circuit of the driving magnet DM of the delayed alarm rotary switch DAR, Fig. 12, and at armature st_2 prepares the circuit of relay PS, Fig. 12, for the reception of pulses received over the conductor 75 17 from the spring set and cam S.

Assuming now that the calling subscriber fails to dial before the reception of the first pulse after the operation of relay ST, relay PS will be allowed to operate its make-first armature ps_1 over its left-hand winding and to operate its remaining armatures over both its windings in series at the cessation of the earth pulse; at armature ps_2 relay PR is connected to conductor 17 so that on the reception of the next earth pulse relay PR operates. Relay PR at armature pr_1 allows relay FM to operate and this relay at armature pm_1 prepares the circuit of the driving magnet DM of the rotary switch DAR. Upon the cessation of the earth pulse, relay PR releases, and at armature pr_1 breaks the circuit of relay PM and completes the circuit of the magnet DM. Relay PM is slow to release due to the presence of the copper slug fitted onto the heel end of its core and keeps armature pm_1 operated for a period sufficient to ensure the correct operation of the magnet DM. The magnet DM is therefore fully energized upon the release of relay PM and steps the wipers of the rotary switch DAR to the next set of bank contacts. Each succeeding pulse applied to conductor 17 by the "S" pulse cam will cause the wipers to be stepped on in like manner until that contact is reached to which conductor 18 is connected, in this case after four steps have been taken. Earth from the wiper 1b is now transmitted along conductor 18 to operate relay ZP, Fig. 2, over its lower winding, via operated armature sp_2 . Relay ZP at armature zp_1 breaks the holding circuit of relay H to the line finder, Fig. 2, and at armature zp_2 disconnects conductor 13, thus allowing relay LR, Fig. 1, to release. Relay CO which was energized in series with relay LR being slow to release will remain held over the circuit including the subscriber's instrument when relay LR releases, via resting armature l_3 , operated armature co_3 , subscriber's line and instrument, resting armature l_2 to earth. Earth is now extended over conductor 20 via operated armature co_3 , resting armature l_3 and the supervisory lamp LP common to the group of subscribers' line circuits to which this particular line 105 circuit belongs, to operate relay LA, Fig. 11. Relay LA in operating at armature l_1 applies earth to conductor 21 to originate a supervisory alarm, the operation of which will be described later.

Returning now to the finder, relay H in releasing breaks the connection to the local first selector at armatures h_3 and h_7 so that relay 2A in the latter switch will restore and when relay 2B has consequently restored due to the restoration of armature 2a1 earth from resting armatures 1h3 and 2a1, winding of relay 2C, and resting armature 2b3 will be connected to conductor 22 and then via the busy and test jack BTJ, Fig. 2, operated off-normal springs 1N1 of the finder switch to operate the release magnet 1Z of the finder switch in series with relay 1RA, Fig. 12, over conductor 98. If due to any fault, such as a mechanical defect or the like, correct release of the finder switch does not take place, relay 1RA will remain operated and give an alarm in a 140 manner shortly to be described. Assuming, however, that no such defect exists the finder switch and the local first selector will fully restore to normal. It should be pointed out that while the PG condition exists in the calling subscriber's line circuit his line is busied on the final selector banks by earth from resting armature l_2 , resting armature bd_1 , circuit including the subscriber's instrument, resting armature bd_2 , operated armature co_2 , resting armature l_3 , lower winding of 145

relay LR, private normal conductor 12 to the final selector bank multiple. The busy relay 3G in the final selector, Fig. 4, is designed to operate in an extension of this circuit, while its resistance is of such a magnitude as to prevent the operation of relay LR over its lower winding in this circuit.

Considering now the case in which the calling subscriber dials before the reception of the first "S" pulse, he will have been receiving dial tone from earth, left-hand winding of dial tone transformer DTT, Fig. 13, conductor 99, normal position of 11th step cam springs 1S1, lower winding of relay 2A, resting armature 1h1, conductor 32, operated armature h3, wiper 2a and bank contact of finder switch, conductor 25, resting armature bd1, subscriber's line and instrument, resting armature bd2, conductor 24, bank contact and wiper 1a of finder switch, upper winding of relay 1M, operated armature h7, conductor 31, resting armature 1h2, upper winding of relay 2A to battery, and when he dials relay 2A will impulse over this circuit and step the vertical magnet 2VM in the well-known manner. It is considered necessary to describe only the digit absorbing function of this selector as apart from this feature the circuit is of the well-known group selector type employing break rotary interrupter springs 2R. By adjusting the normal post springs NP1 and NP2 to operate on a certain level this switch is rendered capable of absorbing the digit associated with that level. Relay 2G, Fig. 3, will release when springs NP1 break so that when relay 2C restores a circuit is completed for the release magnet 2ZM of this selector as follows: earth, resting armature 2c1, operated normal post springs NP2, resting armature f2, operated off-normal springs 2N2, release magnet 2ZM to battery via conductor 33 and relay 2RA, Fig. 12, so that the switch shaft is restored to normal. The release magnet in operating the release magnet springs 2Z ensures the continuation of this circuit until the off-normal springs 2N2 are opened. When the latter springs break relay F operates over its lower winding in a circuit extending from earth, operated release magnet springs 2Z, resting armature f2, lower winding of relay F, operated armature 2b5, winding of release magnet 2ZM, conductor 33, winding of relay 2RA, Fig. 12, to battery. The release magnet springs 2Z are adjusted to have a long stroke so that they remain closed for a period sufficient to allow relay F to operate its make first armature f1, whereupon it will operate fully over its upper winding in a circuit extending from: battery, upper winding of relay F, operated armature f1, operated armature 2b1 to earth. At armature f2 the release magnet circuit is opened to enable the shaft to be stepped upon the reception of the next series of impulses. It should be pointed out that due to the operated armature f3 short circuiting springs NP1 the switch will not be forcibly released again should the same digit be dialled a second time. In this case relay 2G will remain operated after the cessation of vertical impulses so that when relay 2C restores the rotary magnet 2RM will operate over a circuit extending from battery, winding of rotary magnet 2RM, operated armature 2g2, resting contacts of armature 2c2, operated armature 2b1, to earth in order to "cut-in" the wipers and to break the circuit of relay 2G at rotary interrupter springs 2R. Rotary hunting motion will then take place in the manner well-known to those skilled in the art until a free final selector, Fig. 4, is found, whereupon relay 1H of the local

first selector will operate in series with relay 2G, since it is no longer shunted by the busying earths encountered by wiper 3c in passing over the private contacts of engaged final selectors, and at operated armatures 1h and 1h2 will prepare the circuit extending over conductors 35 and 36 of relay 3A of the combined regular and toll final selector, Fig. 4, which has just been seized.

Relay 3A will thereupon operate in series with the subscriber's line and instrument via resting contacts of armatures d3 and d4 in series with the windings of relay AA which are connected in opposition to each other so that relay AA cannot operate in this circuit. Relay 3A in operating at armature 3a1 completes circuits for relays 3B and 3C, the circuit of the latter relay extending over off-normal springs 3N1, resting armature e1, and upper winding of the relay to battery. At armatures 3b1 and 3c1 a circuit is prepared for the vertical magnet 3VM of the final selector over the lower winding of relay 3C while at armature 3b2 earth is applied to the release trunk conductor 37 to guard the final selector and also to hold relay 1H in the local first selector, relay H in the finder switch and relays LR and CO in the subscriber's line and cut-off circuit. At armature 3b5 the motor start conductor 16 is earthed via resting armature 1f4. At the first interruption from the calling party's dial, relay 3A restores but relay 3B remains operated by virtue of its heel end slug and a circuit is now completed from earth, resting armature 3a1, operated armature 3b1, operated armature 3c1, lower winding of relay 3C, resting armature e2, winding of vertical magnet 3VM to battery. The vertical magnet 3VM therefore lifts the shaft and wipers to the first level thus allowing the off-normal springs 3N1 to break the original operating circuit of relay 3C which however remains operated throughout the train of impulses which follow due to the impulse currents in its lower winding as it is provided with a slug fitted on the heel end of its core. Subsequent impulses re-act on the vertical magnet 3VM in a similar manner to the first, and the shaft and wipers are therefore stepped to the required level, relay C restoring after the completion of the last impulse and preparing the circuit of the rotary magnet 3RM. Relay 3A responds to the final series of impulses dialled by the calling party and transmits impulses over the following circuit: earth, resting armature 3a1, operated armature 3b1, resting armatures 3c1, 3g2, 2t5, 2d2, 2h2 and 3d3, winding of rotary magnet 3RM to battery. Relay E operates over its upper winding in parallel with the rotary magnet 3RM and at operated armature e2 short-circuits its own lower winding, this having the effect of a heel end slug and relay E is thus enabled to remain operated throughout the train of impulses. Relay E on operating, at armature e3 short-circuits armatures 2t5, 3g2 and 3c1 so that any subsequent operation of relays 2TB, 3G or 3C due to the wipers of the final selector passing over engaged contacts, or due to other causes which will become apparent later, will not result in the clipping of the pulses. The six wipers 1d to 6d of the final selector are thus stopped to the required line.

Considering now the case in which the required subscriber is engaged on another call, wiper 3d will encounter earth on the associated bank contact and owing to the fact that relay E remains operated for an instant after wiper 3d has reached the contact, relay 3G will now operate

from battery, winding of relay 3G, resting armature m_1 , operated armatures 3b3 and e_4 , resting contacts of armature 2h3, resting armatures 2tb2 and m_2 , wiper 3d and bank contact associated with called subscriber, conductor 38, operated armature 1b1 in called subscriber's line and cut-off circuit, Fig. 5, to the release trunk conductor 39 which is earthed by a selector or final selector in the train of switches in use for the call upon which the called subscriber is engaged. It should be mentioned that in certain conditions, for instance when the called subscriber is busied on a permanent loop condition (which has already been described) the wiper 3d may not encounter a full earth and for this reason relay 3G is fitted with a lightly tensioned make-first armature 3g1 which relay 3G may operate even on a high resistance earth. When relay E restores, however, relay 3G operates fully over a circuit extending from: earth, operated armature 3b2, operated armature 3g1, resting armature dr_1 , resting contacts of armature e_4 , operated armature 3b3, resting armature m_1 , winding of relay 3G to battery and at armature 3g2 disconnects the impulsing circuit of the rotary magnet 3RM so that further dialling will not affect the latter while at armature 3g3 relay 3G applies busy tone, which may be a high pitched tone interrupted at short regular intervals, from conductor 40 via resting armatures dr_2 and e_5 , speaking condenser QB and thence to the calling subscriber via the calling switch train.

It should be pointed out here that the equipment utilized in the generation and distribution of ringing and the various tones required in the working of the system, Fig. 14, is substantially the same as that described in British Patent No. 351,549. It is not intended, therefore, to describe this in detail, and furthermore in order to avoid undue complication of the drawings certain conductors utilized in the transmission of tones and the like have not been shown extended to the ringing and tone circuit, Fig. 14, although it should be understood that these conductors actually do extend thereto.

When the calling subscriber hears the busy tone he must thereupon hang up his receiver and, if he wishes, recall after an interval. Upon the removal of the direct current circuit from across conductors 35 and 36 consequent upon the calling subscriber restoring his receiver relay 3A will restore and allow relay 3B to restore after its slow release period. The release magnet will now operate over a circuit extending from: earth, resting armatures 3a1, 3b1, d_1 , operated off-normal springs 3N1, winding of release magnet 3ZM, conductor 41, winding of release relay 3RA, Fig. 12, to battery and will therefore cause the shaft and wipers of the final selector to restore to normal, whereupon the circuit of the release magnet 3ZM will be opened when springs 3N1 break. The removal of earth from conductor 37 consequent upon the restoration of armature 3b2 will enable relay 1H of the local first selector to restore and complete the release magnet circuits of the selector and also of the finder switch associated with it, both switches thereupon restoring to normal. Relays LR and CO in the subscriber's line and cut-off circuit are also allowed to restore.

Considering now the case in which the required subscriber is not engaged, relay 3G will not operate as previously described when the final selector wipers reach the correct set of bank con-

tacts so that when relay E restores a circuit will be completed for relay 2H of the final selector over a circuit extending from: earth, operated armature 3b2, resting armature 3g1, lower winding of relay 2H, resting armature e_4 , resting contact of armature 2h3, resting armatures 2tb2 and m_2 , wiper 3d, bank contact, conductor 38, lower winding of relay 1LR, winding of relay 1CO to battery. Relay 2H is enabled to operate its make first armature 2h1 over this circuit so that it will then lock up over its upper winding to earth via the operated armature 2h1 and operated armature 3b4. Relay 2H in operating at armatures 2h4 and 2h5 completes the ringing circuit extending from ring-return battery on conductor 52, resistance YA, resting armature 1f2, operated armature 2h5, resting armature td_4 , wiper 2d and bank contact, conductor 42, resting armature 1bd2, called subscriber's line and calling device, resting armature 1bd1, conductor 43, bank contact and wiper 1d, resting armature td_5 , operated armature 2h4, resting armature 1f3, right-hand winding of relay 1F to earthed interrupted ringing applied to conductor 42. Full earth is also extended to wiper 3d over resting armature dr_3 , operated armature 2h3 and resting armatures 2tb2 and m_2 in order to bus the called subscriber.

The importance of the fact that a full and not a resistance earth is connected when the calling party is not a toll operator will be appreciated later. Ring back tone which is in effect an "echo" of the ringing is transmitted back to the calling subscriber from interrupted ringing conductor 42, right-hand winding of relay 1F, resting armature 1f3, operated armature 2h6, ring-back tone condenser QC, speaking condenser QA, conductor 35, and so out to the calling subscriber to inform him that the wanted subscriber's bell is being rung.

When the called subscriber replies in answer to the ringing the resultant direct current circuit across the conductors 42 and 43 will cause relay 1F to operate its make first armature 1f1 over its right-hand winding and then operate fully over its left-hand winding via operated armatures 1f1 and 3b4. Relay 1F in operating at armature 1f4 removes earth from the motor start conductor 16 and at armatures 1f2 and 1f3 cuts off ringing and switches through the called subscriber's circuit. Due to the operation of armature 1f2, relay D energizes over its right-hand winding and at armatures d_3 and d_4 reverses current in the calling subscriber's circuit in order to meter the call. This is accomplished due to the operation of the meter relay 1M in the line finder circuit, Fig. 2. The lower winding of relay 1M, serving as a polarizing winding, will have been energized via an operated armature h_6 of the line finder but until the calling party replies current in the upper or line winding will have been flowing in the wrong direction for the operation of relay 1M. Upon current being reversed, however, relay 1M operates and at armature $1m_1$ provides earth in order to operate the calling subscriber's meter to register the call over a circuit extending from earth, operated armatures $1m_1$ and h_4 , wiper 4a and bank contact of finder switch, conductor 44, operated armature co_4 , winding of subscriber's meter MTR to battery. The meter operates, thus registering the call and locks up via its operated armature mtr_1 and operated armature co_4 .

Returning now to the final selector, relay D at armatures d_1 and d_2 also prepare circuits which 150

will come into operation in the event of the calling subscriber clearing before the called subscriber at the conclusion of the call. If this occurs relay 3A will restore, and during the slow release period of relay 3B, relay E will operate over its original operating circuit. The rotary magnet 3RM is, however, prevented from operating over this circuit by the operated armature 2h2. Since relay E is a slow release relay by virtue of its lower winding being short-circuited at operated armature e2, it will remain operated for a short period after relay 3B has restored, and at operated armature e4 will disconnect conductor 37 from the source of earth at resting armature dr3, thus allowing the preceding switch train to restore to normal. Upon the restoration of relay E, however, earth will again be extended via resting armature dr3, operated armature 2h3, resting armatures 3b6 and e4, low resistance lower winding of relay 2H, resting armature 3g1, conductor 37, in order to re-guard the final selector against seizure by another selector until the called party has hung up his receiver. Relays 1F and 2H will still remain operated via operated armatures d2 and 1f4 to earth, and a circuit is also completed for the final selector supervisory lamp 1LP from earth, resting armatures 3a1 and 3b1, operated armature d1, supervisory lamp 1LP, conductor 79, winding of relay 1LA, Fig. 13, to battery. Relay 1LA in operating at armature 1la1 closes a circuit for relay 4A extending from battery, lower winding relay 4A, operated armature 1la1, resting armature 4b1, home contact and wiper 2e of delayed alarm rotary switch DBR to earth, whereupon relay 4A locks up in a circuit extending from: earth, operated armature 1la2, supervisory lamp 2LP, common to a group of final selectors upper winding of relay 4A, operated armature 4a1, upper winding of relay 4B to battery. Due to the comparatively high resistance of the upper winding of relay 4A, relay 4B will not be operated in this circuit nor will the supervisory lamp 2LP light. Relay 4A also at armature 4a2 prepares a circuit for the lower winding of relay 4B and at armature 4a3 closes a circuit for relay 1ST. The delayed alarm rotary switch DBR will now proceed to step its wipers around under the control of relays 1PR and 1PM in an exactly similar manner to the delayed alarm rotary switch DAR, Fig. 12, previously described. In this case, however, assuming the called subscriber continues to hold the final selector, the rotary switch makes 20 steps being equivalent to a delay period of three minutes before relay 4B operates over its lower winding via operated armature 4a2, bank contact and wiper 1e of rotary switch DBR, to earth and by short-circuiting the locking or upper winding of relay 4A at operated armature 4a2 causes the latter relay to restore and break the circuit of relay 1ST which thereupon releases and completes the homing circuit of the driving magnet 1DM of rotary switch DBR over a circuit extending from: battery, winding rotary magnet 1DM, magnet interrupter springs 1dm, resting armature 1st1, commoned bank contacts and wiper 4e of rotary switch DBR to earth. The operation of armature 4b2 in addition to causing the release of relay 4A also enables the supervisory lamp 2LP to light since the upper winding of relay 4B is of comparatively low resistance, relay 4B meanwhile energizing in the same circuit. Relay 4B at armature 4b3 provides earth to light the supervisory lamp 3LP this being the main super-

visory lamp for the rack upon which the particular final selector is mounted.

Considering again the final selector, Fig. 4, when the called subscriber hangs up his receiver the consequent release of relay D will complete a circuit for the release magnet 3ZM via resting armature d1, while at the same time the operating circuit of relay 1LA, Fig. 13, is broken, resulting in the release of the supervisory equipment assuming that it is not being held by any other switch in the same condition.

In the event of the called party hanging up before the calling party relay D will restore but relay 3A will remain held by the calling party and retain relay 3B which will in turn hold relays 1F and 2H. The switch supervisory lamp 1LP will now glow over a circuit extending from: earth, operated armature 1f4, resting armature d2, lamp 1LP to battery via relay 1LA as before described.

Having thus described the operations which take place in the various switches in the train when a call is initiated by a subscriber, it is now proposed to describe the additional operations brought into use when a toll operator utilizes the final selector for the purpose of offering a toll call to a subscriber. The toll operator is given direct access to an incoming or toll selector, Fig. 8, by inserting the plug of her cord circuit into a jack JK, Fig. 11, which connects via conductors 45 and 46 with relay 5A, Fig. 8, of the toll selector, and by operating the ring and dial key RDH she is enabled to dial onto this selector and thereby operate the same. A detailed description of the operation of this switch is not necessary since apart from the fact that it does not possess a digit absorbing feature its functions are exactly similar to those of the local first selector, Fig. 3, already described. It should be pointed out that this particular group selector has been designed to enable it to be used when required in conjunction with a finder switch such as that shown in Fig. 2 and already described. In this case conductors 22a, 26a, 27a and 29a would be connected to conductors 22, 26, 27 and 29 respectively of the finder switch.

Assuming now that the toll operator, by manipulating the dial DL associated with her position has operated the toll selector, the latter will hunt for and seize a free combined regular and toll final selector in the well-known manner. As soon as the toll selector has switched, relay 3A will operate but this time relay AA will also operate since in the normal position of the operator's dial DL earth is connected to both speaking conductors through the shunt springs DLS of the dial. The differential effect of the winding of relay AA will, therefore, not now apply, and the relay will operate due to current in its upper winding alone. At armature aal a circuit is closed for relay AD which will operate and complete a circuit at armature ad3 for relay DR which locks up to earth at operated armature 3b4 via its own operated armature dr4. The operator now dials and relay AA will restore as soon as the dial is moved off normal since current will once more flow in opposition in its two windings. Relay AA in restoring will release relay AD. The operation of the vertical and rotary magnets of the final selector takes place in a similar manner to that already described except that during the rotary motion relay 3C re-operates in a circuit extending from: earth, operated armatures dr3 and e1, upper winding of relay 3C to battery. It should be noted

that relay AA will re-operate each time the dial returns to normal.

- Considering now the case in which the required subscriber is disengaged, the call will proceed in a similar manner to that already described except that wiper 3d of the final selector will be guarded by earth via a resistance YB since the direct earth which provided the guard via the resting armature dr3 in the case of a call originated by a subscriber is now removed, for as has been explained relay DR always operates on a call originated by a toll operator. The reason for guarding wiper 3d by a resistance earth instead of a full earth will become apparent when the case is considered of the wanted subscriber being already busy on a toll call when his number is dialled by a second toll operator. In this case it is desirable that the second toll operator should not interfere with the toll call in progress. Since all toll calls, whether originated by a subscriber or otherwise, involve his being called by a toll operator, conductor 38 in the engaged subscriber's line circuit will be busied by earth via the "YB" resistance of the final selector engaged in the call. When, therefore, a final selector on being operated by a second toll operator encounters resistance earth via wiper 3d, relay 3G will operate over a circuit extending this earth from: battery, winding of relay 3G, resting armature m1, operated armatures 3b3 and e4, resting armatures 2h3, 2tb2 and m2, wiper 3d, contact of final selector bank, bank multiple wiring, contact of bank of the final selector already being used in the toll call, wiper 3d and the following equivalent relay armatures of this latter switch, resting armature m2, resting armature 2tb2, operated armature 2h3, (since relay 2H of the final selector will have operated), resistance YB to earth. When relay E of the testing final selector restores the circuit of relay 3C is disconnected but the latter remains held for a short period by virtue of its slug and during this period the following connections will now radiate from wiper 3d and the bank contact upon which it is resting:
- (1) Wiper 3d, resting armature m2, operated armature 3g6, resting armature 2tb4, operated armature dr1, resting contacts of armature e4, operated armature 3b3, resting armature m1, winding of relay 3G to battery.
  - (2) Wiper 3d, bank contact, conductor 38, lower winding of relay 1LR, winding of relay 1CO to battery.
  - (3) Wiper 3d, bank contact, bank multiple wiring via the circuit previously outlined to earth via resistance YB in the other final selector.
  - (4) Wiper 3d, resting armatures m2, 2tb2, resting contacts of armature 2h3, resting armature e4, operated armatures 3c2 and 3g7, upper winding of relay 2TB, operated armature 3b4 to earth.
- Current from battery via (1) and (2) in parallel flows to earth via (3) and (4) in parallel so that relay G remains held and relay 2TB operates its make first armature 2tb1, and then operates fully over both its windings in series to earth via operated armature 3b4. At armature 2tb4 the holding circuit of relay 3G is broken so that this relay restores. Toll busy tone which may be in the form of a high pitched tone substantially of the same frequency as ordinary busy tone but interrupted more times per second is now applied to the speaking conductor 36 for transmission to the calling toll operator over a circuit extending from: toll busy tone conductor 47, operated armature 2tb5, resting armature 3g3, operated armature dr2, resting armature e5,

speaking condenser QB to speaking conductor 36. The operator must then release the connection and re-call after an interval.

Reverting to the instant when the toll operator's dial returns to normal at the end of the transmission of the rotary impulses, as previously mentioned, relay AA re-operates and re-energizes relay AD which thereupon extends earth via operated armatures ad4 and 3g9, resting armature ts2, lower winding of relay TS to battery. Relay TS operates its make-first armature ts1 only, its upper winding then being short-circuited by earth via operated armatures ts1, 3b4 on one side, and by earth via operated armatures ad4 and 3g9, and resting armature ts2 on the other side. It will be appreciated later that a condition may obtain when an operator having broken down a call to the required subscriber, the subscriber's conductor 38 may remain fully earthed by the final selector of the local calling party which may not restore immediately.

Assuming this to be the case the operating conditions for relay 2TB previously described would not exist and yet it is necessary to send back to toll busy tone to the operator who is making the call. This is accomplished in the following manner:

When the ring and dial key RDK, Fig. 11, is restored to normal, relay AA restores releasing relay AD which in turn removes the short circuit from the upper winding of relay TS thus allowing this relay to operate fully over both its windings in series. At armature ts3 a circuit for relay 2TB is completed extending from: earth, operated armature 3b4, upper-winding of relay TB, operated armature 3g7, resting armature 3c2, operated armature ts3, resting armature td6, wiper 6d and bank contact to battery via a resistance in the other final selector which has previously broken down a local call to the subscriber. The presence of this battery will be made apparent later. Relay 2TB thereupon operates in this circuit and locks up as previously explained performing its function of transmitting toll busy tone to the calling toll operator.

Considering now the case in which a toll operator desires to offer a toll call to a subscriber who happens to be engaged on a local call, in this case conductor 38 in the subscriber's line circuit will be connected to full earth either from the release trunk conductor 39 if he is the originator of the call or from the calling final selector if he is the called subscriber in the local call. In either event, relay 3G in the final selector under control of the toll operator will operate as before described and lock up when relay E restores. The upper winding of relay 2TB will now be shunted by direct earth from wiper 3d so that relay 2TB will not operate. Relay 3C restores at the end of its slow release period and relay TS having operated its make first armature ts1 as previously described operates fully when the ring and dial key RDK is restored and earth thereby removed from both speaking conductors. The following "cut-in" transmission circuit is now established: conductor 35, speaking condenser QA, operated armatures 3g4 and dr5, resting armatures 3c3 and td5, wiper 1d and bank contact, conductor 43, resting armature 1bd1, Fig. 5, required subscriber's line and instrument, resting armature 1bd2, conductor 42, bank contact and wiper 2d, resting armatures td4 and 3c4, operated armatures 3g3 and dr2, resting armature e5, speaking condenser QB to conductor 36, conductors 35 and 36 leading, of course, via the switch train to the

toll operator's cord circuit. The toll operator is thus enabled to speak to the subscriber and to offer the toll call. It should be pointed out that the operated armatures $3g4$ and $3g5$ serve to disconnect the windings of relay D from the called subscriber's line thus preventing the possibility of a lock-up condition which would otherwise occur if current happened to be reversed on the called line. Relay D will, however, operate over one winding in a circuit extending from: earth, right-hand winding of relay D, operated armatures $3g5$ and $td4$, resistance YC to battery in order to reverse the current in the calling loop for the purpose of supervision at the operator's position.

The operator having offered the toll call may in the event of its acceptance by a required subscriber follow either of the two following procedures (a) she may ask both local parties to clear the line by hanging up their receivers, or (b) she may break down the local connection if this course is found to be necessary. If she follows the first procedure, earth will be removed from the conductor 38 in the required subscriber's line circuit, Fig. 5, when the line becomes clear and relay $3G$ will therefore release. The call will thereafter proceed as though it were a normal one to a disengaged subscriber, relay $2H$ operating and connecting earth via resistance YB , operated armature $2h3$, resting armatures $2tb2$, and $m2$, wiper $3d$ and bank contact thus causing the subscriber to become "trunk busy" to other final selectors seeking to establish a connection with him. If, however, the operator follows procedure (b) she will immediately depress the toll break-down key BDK , Fig. 11, associated with the cord circuit, and by so doing will cause earth to be again connected to both speaking conductors leading to the final selector. The consequent operation of relay AA followed by relay AD completes a circuit extending from: earth, operated armatures $ad4$ and $3g9$, operated armature $ts2$, lower winding of relay TD to battery. Relay TD operates its make first armature $td1$ and then operates fully when relay AD restores as a result of the operator releasing the key BDK . Relay TD on operating at armature $td3$ removes a short circuit from relay M , which is now enabled to operate in a circuit extending from: earth, operated armature $td2$, resting armature $2h2$, winding of relay M , winding of the rotary magnet $3RM$ to battery, afterwards locking up via operated armature $m2$ to earth on wiper $3d$. It should be pointed out that the comparatively high resistance of relay M prevents the operation of the rotary magnet $2RM$ in this circuit. At operated armatures $td4$ and $td5$ the speaking conductors are switched from wipers $2d$ and $1d$ to wipers $5d$ and $4d$ respectively. At operated armature $td7$ the ring-trip relay $1F$ is tripped since interrupted ringing will not be required on this call, while at operated armature $td8$ battery via resistance YC is connected to wiper $6d$, and from thence via the bank contact to conductor 48 to operate relay $1BD$ in the subscriber's toll break-down relay circuit, Fig. 5. It should be mentioned that this battery connection also establishes the toll busy test condition on the subscriber's line as previously described. The operation of relay M at armature $m3$ closes a circuit for the operation of relay $2H$ over its upper winding which extends to earth at operated armature $3b4$. Relay $2H$ is slow to operate so that relay M has time to operate and lock before its original energizing circuit is broken at operated armature $2h2$. Also at operated

armature $m1$ the circuit of relay $3G$ is broken so that this relay will restore. The operation of relay $1BD$, Fig. 5, results in the required subscriber being disconnected at operated armatures $1bd1$ and $1bd2$ from the local call, irrespective of whether this had been an outgoing call originated by him or a call incoming to him over conductors 42 and 43. Conversation may now take place with the required subscriber over conductors 49 and 50.

Assuming that the subscriber had been engaged by virtue of having originated a call, conductor 38 in his line circuit would have been earthed, via operated armature $1r1$ and the earth applied to conductor 39 by the foremost switch in his calling train and relay M would have become locked up to this earth as has already been described. The disconnection of the subscriber's circuit from the foremost switch in the local calling train by the application of battery on wiper $6d$ would have caused the latter to release, but the fact that relay M remains locked up until earth disappears from the conductor 38 prevents the toll operator's final selector from extending its guarding earth via resistance YB , operated armature $2h3$, resting armatures $2tb2$ and $m2$ to wiper $2d$ and conductor 38 until the intermediate selectors in the local calling train have released and allowed relay M to restore. This guarding earth would otherwise hold the switches of the local calling train.

If for any reason the toll operator wishes to re-call the subscriber after he has hung up, she may do so by once again operating the toll breakdown key BDK in her cord circuit Fig. 11, whereupon relays AA and AD in the final selector, Fig. 4, will again operate. Relay AD at armature $ad1$ connects continuous ringing tone from conductor 51 via operated armatures $ad1$, $1f3$ and $2h4$ via armature $td5$ and wiper $4d$ or $1d$ according to whether the "toll breakdown" has taken place or not, bank contact, conductors 49 or 43, subscriber's line and calling device, conductors 50 or 42, bank contact, wiper $5d$ or $2d$, armature $td4$, operated armatures $2b$, $1f2$ and $ad2$ to ring return battery via resistance YA and conductor 52.

After a toll call if the operator clears before the called subscriber, relays $3A$ and $3B$ will restore, while relay E being momentarily energized will remove earth from conductor 37, thus allowing the group selector train to restore. Conditions are similar to those already described, but it should be pointed out that the release of relay B will at armature $3b4$ short-circuit resistance YB so that full earth will be connected to the conductor 38, after the operator restores in order to permit another toll operator to "cut-in" on the subscriber's line if necessary.

If the called party clears down before an operator, the consequent release of relay D will reverse current over the speaking conductors thus giving the necessary supervision in the operator's cord circuit. The toll selector, Fig. 8, may have access over certain levels to repeaters, Fig. 9, outgoing to another automatic exchange. In order to enable the toll operator to break down local connections at the distant exchange the repeater is arranged to repeat over the outgoing speaking conductors the connection of earth potential to both the incoming speaking conductors. When this repeater is seized by the toll selector the operator's loop will be extended via conductors 53 and 54 to operate relay $6A$ over both windings in series with the windings of relay $1AA$ which is a differentially wound relay similar in operation to relay AA in the final selector. As soon

as the repeater is seized therefore, relays 6A and 1AA will then fully operate resulting in the operation of relay 6B at armature 6a1, and relay 1AD at armature 1aa1.

- 5 The operation of relay 1AD at armatures 1ad1 and 1ad2 applies earth via resistances 1YB and 1YC to conductors 56 and 57 leading via the main and extended alarm group, Fig. 10, to the trunk line terminating at the distant exchange.
- 10 The operation of the final selector at the distant exchange is thereby influenced in a manner similar to that previously described. Relay 6B on operating at armature 6b1 applies earth to conductor 55 to guard the repeater and to hold preceding switches, at armature 6b2 energizes the polarizing winding of the shunt field relay 1D and at armature 6b3 prepares the circuit of relay 5C. When the operator dials relay 1AA restores and relay 6A impulses. The restoration of relay 1AA allows relay 1AD to restore and thus at armature 1ad1 to include the impulse repeating armature 6a2 in the circuit outgoing to the distant exchange. Relay 5C operates on the first impulse and at armature 5c1 short-circuits the retard IM and the left-hand or line winding of relay 1D thereby nullifying the deleterious effect their combined impedance would otherwise have on the repeating of impulses to the distant exchange. The resistance 1YA connected across the resting contacts of armature 5c1 prevents a false impulse being given during the transit time of the springs.

When the called party replies the reversal of current over the circuit including conductors 56 and 57 causes relay 1D to operate and at armature 1d1 energizes its relief relay 1DR which latter relay at armatures 1dr1 and 1dr2 reverses current over conductors 53 and 54 to provide supervisory or metering conditions.

40 Referring now to Fig. 10 which represents the main and extended alarm equipment, when a fault arises in the main exchange equipment, the associated supervisory circuit is arranged to connect earth to the appropriate relay (RF, 5RA, SY, FA or LV). By way of example one particular fault namely the release alarm may be considered.

Returning to Fig. 12 if any of the switches served by relays 1RA, 2RA, 3RA or 4RA fail to release the appropriate "RA" relay, for example 50 1RA, will remain operated and at armature 1ra1 will earth the motor start conductor 16, while at armature 1ra2 it will connect the left-hand winding of relay 7A to the nine second "S" pulse conductor 17, along which are transmitted earth pulses at intervals of 9 seconds in the manner already described. Armature 1ra3 prepares the circuit of the release lamp 1RLP associated with the group of switches fed by relay 1RA. Upon the reception of the first earth 55 pulse relay 7A operates and locks up over its right-hand winding at armature 7a1 in a circuit including the right-hand of the winding of relay 7A in such that relay 7B will not operate nor will the lamp light in this circuit. At armature 7a2 the left-hand winding of relay 7B is connected to the "Z" pulse conductor 64 and upon the reception of the first pulse relay 7B operates and at armature 7b1 breaks the original operating circuit of relay 7A. Also at armature 60 7b2 the holding winding of relay 7A is short circuited so that the latter relay releases. Due to the low resistance of the right-hand winding of relay B the lamp 1RLP will now light, thus indicating which group of switches include the 65 faulty one. Armature 7b3 serves to light the

main release alarm lamp RLP, while at armature 7b4 applies earth to conductor 59 to operate relay 5RA in Fig. 10, which at armature 5ra1 applies earth to the motor start conductor 16 and at armature 5ra2 connects toll busy tone 80 from conductor 47 via resting armatures 1v2, rf2 and fa2, condenser QH, operated springs of alarm changeover key ACK1, conductor 89 to a, jack not shown fitted on the toll board, where the tone may be observed by an operator via a regular cord circuit. In similar manner a failure of the ringing supply will result in earth being applied to conductor 58 to operate relay RF which in turn will apply an indicating tone, which may be in this instance busy tone, to the jack aforementioned. Similarly the blowing of a fuse will result in the operation of relay 1FA, Fig. 10, followed by the operation of relay FA which at armature fa2 applies ringing tone received over conductor 42 and condenser QK 95 to the jack on the toll board. Finally if the main voltage falls below a specified minimum value this will result in the release of relay 8A, Fig. 10, which at armature 8a1 closes the circuit of relay LV. Relay LV on operating at armature 1v2 applies to the jack "low volt" indicating tone, which in this instance may be N. U. tone characterized by a continuous high pitched tone of the same frequency as busy tone.

It will be seen therefore that by plugging into 105 the jack an operator may determine immediately the nature of the fault. It should also be pointed out that in the event of two or more alarm relays, that is to say, relays associated with different kinds of fault being operated at 110 the same time the tone associated with the most urgent fault is alone connected to the jack.

Alarms may also be extended from a distant exchange to the exchange under consideration. When the alarm change-over key ACK is normal, any fault arising in the distant exchange will result in earth via a relay not shown being applied to the junction conductor 60 to operate relay CX, Fig. 10, via resting armature 2co1, and normal springs of the alarm changeover key 115 ACK2. Relay CX in operating will light a lamp not shown indicating to the exchange attendant the presence of a fault at the remote exchange. By plugging into the test jack TJ, Fig. 10, with a hand telephone the attendant may listen to 120 the tone sent over the junction, via an operated armature of the alarm relay at the distant exchange which is energized as a result of a fault. The operation of the alarm change-over key ACK transfers alarms to the toll board whereupon they will be observed by an operator as 125 already described. It will be seen that in Fig. 10 the junction used for the extension of alarms is one also associated with a repeater as in Fig. 9. Whenever this repeater is in use relay 130 2CO will be operated via conductor 55 from earth at operated armature 6b1, Fig. 9, so that the alarm equipment will be disconnected from the conductors and the repeater connected thereto at operated armatures 2co1 and 2co2. This will 135 result in the distant end of the junction being disconnected from the alarm equipment at the distant exchange and connected to an incoming selector therein.

Spare or unallotted levels on group selector 140 banks are connected to the spare level equipment with N. U. tone, shown on the right-hand half of Fig. 8 and comprising relays 9A and 9B. The operation of relay 9A when the equipment 145 is seized applies number unobtainable, that is, 150

- N. U. tone via condenser QN and operated armature 9a1 to the group selector bank contact and wiper for transmission to the calling party. Spare or unallotted numbers on final selector banks will be connected via conductors 65 and 66 to relay N. U. shown in the lower part of Fig. 5. The operation of this relay to the earth applied to wiper 3d of the final selector will result in the application of N. U. tone on conductor 78 via condenser QN1 to conductor 65 for transmission via the final selector and calling switch train to the calling party.
- Fig. 1a of the drawings shows an alternative line circuit for use when it is not required to provide the arrangement for disconnecting the finder switch if the calling subscriber does not dial within a predetermined period. It will be noted that the extra relay BD is dispensed with and that only the usual line relay and cut-off relay are required. The operation of the line circuit in connection with a finder such as that shown in Fig. 2 of the drawings can be readily traced and it is only necessary to point out the operations which take place when a toll operator wishes to connect with a line busy in a local call. In this case, battery fed over conductor 12 serves to shunt the lower winding of relay LR so as to cause it to release and thus to disconnect the calling line from the local switches. It will be noted that the line contacts of relay LR that is, armatures 1r3 and 1r4 in Fig. 1a, are inserted between two line banks so that the release of relay LR is also effective in disconnecting the wanted subscriber's line from the local switches when he is the called party in the local connection.
- What I claim as new and desire to secure by Letters Patent is:—
1. In a telephone system, a line which may be either busy or idle, an automatic switch, means for operating said switch to extend either a local or a toll connection to the line when the line is idle or to extend toll connection to the line when the line is engaged in a local connection, a relay individual to the line for releasing a local connection in which the line is engaged, and means in said switch for controlling said relay.
  2. In a telephone system, a line which may be either busy or idle, an automatic switch, means for operating said switch to extend either a local or a toll connection to the line when idle or to extend a toll connection to the line when engaged in a local connection, a relay individual to the line, and means controlled over a toll connection extended through said switch for operating said relay to release a local connection in which the line is engaged.
  3. In a telephone system, a line engaged in a connection, a relay individual to the line energized to complete said connection, means for extending a second connection to the line, and means controlled over said second connection for deenergizing said relay to release the first connection.
  4. In a telephone system, a line, a relay individual to the line, means for energizing the relay responsive to the initiation of a call on the line, means for maintaining the relay energized throughout the call, means for extending a second call to the line, and means responsive to the extension of said second call for releasing said relay to free the line from said first call.
  5. In a telephone system, a line, a relay individual to the line, means for energizing said relay responsive to the line becoming engaged in either an incoming or an outgoing connection,
- means for extending a further connection to the engaged line, and means controlled over said last connection for deenergizing said relay to release said first connection.
6. In a telephone system, a line engaged in a connection, a relay individual to the line energized to complete the connection, means for extending a second connection to the engaged line, and means controlled over the second connection for shunting said relay to release the first connection.
  7. In a telephone system, a first line and a second line, a relay individual to the first line, contacts on said relay for connecting the first line to the second line to extend a connection thereover, means for initially energizing said relay over the first line, means for maintaining said relay energized over the second line, means for extending a further connection to the first line when the same is engaged in a connection, and means controlled over said further connection for deenergizing said relay to disconnect the first line from the second line to thereby interrupt the initial connection.
  8. In a telephone system, a subscriber's line having two branches normally physically connected thereto, means for extending a local connection to the line over one branch, means for extending a toll connection to the line over the other branch, and means responsive to the extension of a connection to said other branch for disconnecting said one branch from the line.
  9. In a telephone system, a line having two branches, means for extending local connections to the line over one branch, means for extending toll connections to the line over either branch, and means dependent on the idle or busy condition of the line for determining the particular branch over which a toll connection will be extended.
  10. In a telephone system, a line accessible over one route in local or toll connections and accessible over a second route in toll connections, means responsive to the establishment of a local connection to the line for preventing the establishment of subsequent connections of either class over said one route without preventing the establishment of toll connections over the second route, and means responsive to the establishment of a toll connection to the line over either route for preventing the establishment of subsequent connections of either class over either route.
  11. In a telephone system, a line, a branch of said line accessible for local connections and for toll connections, and a second branch of said line accessible for toll connections only when a local connection is established over the first branch.
  12. In a telephone system, a line, a branch of said line accessible for local connections and for toll connections, a second branch of said line accessible only for toll connections, and means controlled over said second branch for disconnecting said first branch from the line.
  13. In a telephone system, a line, a branch of said line accessible for local connections and for toll connections, a second branch of said line accessible only for toll connections, and a relay individual to the line for disconnecting said first branch from the line.
  14. In a telephone system, an automatic switch provided with two separate sets of wipers, means for extending connections of two classes through said switch, and means dependent upon the class of connection extended for determining the par-

- ticular set of wipers to be employed in the connection.
15. In a telephone system, an automatic switch provided with two separate sets of wipers, means for operating the switch to extend local calls over only one set of wipers, and means for operating the switch to extend toll calls over either set of wipers. 80
16. In a telephone system, an automatic switch provided with two separate sets of wipers, means for extending calls of two classes through said switch to a called line, and means dependent jointly on the class of the call and on the busy or idle condition of the called line for determining the particular set of wipers to be employed in the call. 85
17. In a telephone system, an automatic switch provided with two separate sets of wipers, a line which may be either idle or busy, means for operating said switch to extend a connection to said line, and means dependent on the idle or busy condition of the line for determining the particular set of wipers to be employed in the connection. 90
18. In a telephone system, an automatic switch, two separate sets of wipers for the switch, a called line which may be either idle or busy, means for operating said switch to extend a connection over one set of wipers to said line when idle, and means for operating said switch to extend a connection over the other set of wipers to said line when busy. 100
19. In a telephone system, an automatic switch provided with two separate sets of wipers, called lines, means for operating said switch to extend a local connection to an idle called line over one set of wipers, means for operating said switch to extend a temporary talking connection over said one set of wipers to a line busy in a local connection, and means for operating said switch to extend a toll connection over the other of said sets of wipers to the line with which said temporary connection was established. 110
20. A telephone system as claimed in claim 19 in which the local connection and the temporary connection are interrupted responsive to the establishment of the toll connection. 115
21. In a telephone system, a combination local and toll connector switch provided with two separate sets of wipers, means for operating the switch to extend a local connection to a line over one set of wipers or to extend a toll connection to the line over the other set of wipers, and means including a differential relay in the switch for determining whether the connection extended is to be a local connection or a toll connection. 120
22. A telephone system as claimed in claim 21 in which a toll connection may be extended to a line engaged in a local connection and the said local connection may be forcibly released. 125
23. A telephone system as claimed in claim 21 in which a characteristic signal is transmitted 130
- to operate the differential relay in the switch to enable the switch to extend a toll connection to a line engaged in a local connection and a similar signal is subsequently transmitted to interrupt the local connection in which the called line is engaged. 135
24. In a telephone system, a combination local and toll connector switch provided with two separate sets of wipers over which local and toll calls are extended, respectively, to a called line, a differential relay in the switch for initially determining whether a local or a toll connection is to be extended, and means subsequently controlled by said relay for applying ringing current to the called line. 140
25. A telephone system as claimed in claim 24 in which a toll connection may be extended to a line engaged in a local connection and in which the differential relay also controls the forced release of the said local connection. 145
26. In a telephone system, a combination local and toll connector switch provided with two separate sets of wipers each including a test wiper, two test relays, a circuit for one relay including the test wiper of one set, a circuit for the other relay including the test wiper of the other set, a local busy tone circuit controlled by said one relay, and a toll busy tone circuit controlled by said other relay. 150
27. A telephone system as claimed in claim 26 in which the switch is provided with a relay adapted to feed battery to a called line and in which the battery feed relay is disconnected by the first of the test relays. 155
28. In a telephone system, calling lines and a called line, a combination local and toll connector switch provided with two separate sets of wipers, means controlled over a calling line for operating the switch to extend a local connection to said called line over one set of wipers, means controlled over a different calling line for operating the switch to extend a toll connection to said called line over the other set of wipers, and means for releasing the switch in either connection responsive to both the calling party and the called party releasing. 160
29. In a telephone system, an automatic switch provided with two separate sets of wipers, contacts accessible to one set of wipers, other contacts accessible to the other set of wipers, multiple connections between said contacts, and a relay for opening said multiple connections. 165
30. In a telephone system, an automatic switch provided with two separate sets of wipers, a set of bank contacts accessible to the first wiper set, a set of bank contacts accessible to the second wiper set, multiple connections between said contact sets, a relay connected to one contact set, and contacts on said relay for opening said multiple connections. 170
